TRAIN CONTROL SYSTEM FOR RAILROADS

Filed Aug. 8, 1927

FIG. 1

Fig. 2

R. C. LEAUE, INVENTOR
BY Nels W. PESTON, ATTORNEY
his

UNITED STATES PATENT OFFICE.

RICHARD C. LEAKE, OF ROCHESTER, NEW YORK, ASSIGNOR TO GENERAL RAILWAY SIGNAL COMPANY, OF ROCHESTER, NEW YORK.

TRAIN-CONTROL SYSTEM FOR RAILROADS.

Application filed August 8, 1927. Serial No. 211,477.

This invention relates in general to railway train control systems, and has more particular reference to an intermittent automatic inductive alternating current type of control system.

In one form of intermittent inductive train control system to which the present invention is applicable, a brake applying or train movement restricting device is controlled in accordance with traffic conditions ahead by means of inductively related trackway inductors and a car-carried receiver. In such systems it is most desirable that the necessary inductive co-action between the trackway and car-carried devices take place with certainty and uniformity.

With the above and other objects in view, it is proposed, in accordance with this invention, to provide an inductor and receiver of an improved type.

More specifically, the invention provides a trackway inductor formed either of two parallel bars of magnetic material, or a single bar of magnetic material, with means for controlling it in accordance with the traffic conditions ahead, and a receiver comprising a core of rectangular annular form carrying primary and secondary coils thereon in a particular relationship to each other.

Further objects, purposes, and characteristic features will appear as the description of the invention progresses, reference being had to the accompanying drawings, showing solely by way of illustration, two embodiments of the invention. In the drawings:

Fig. 1 is a schematic showing of one form of the invention as applied to a train control system; and

Fig. 2 is a schematic showing of a modified form employing a different form of inductor.

Referring to the drawings, and first to Fig. 1, a section of trackway is shown comprising track rails 1 separated into signalling blocks by means of insulating joints 2, each block having a usual track battery 3 connected across the rails at its exit end, and a wayside signal actuated at the entrance end and shown, in the present instance, as a semaphore type of signal. Obviously the signals could be of some other type, and the various controlling circuits and devices for the signals can be of any usual or desired form and hence it has not been deemed necessary to show or describe them.

Positioned alongside the track, adjacent the entrance end of each block, is an inductor including, in the form of Fig. 1, two parallel bars 6 of magnetic material each of which is furnished with a coil 7 which coils are connected in series with each other and included in circuit with a condenser 8 and contact finger 9 and front contact of the adjacent track relay. The condenser 8 is so chosen as to tune the inductor circuit for the frequency of alternating current employed in connection with the co-acting receiver. Under clear traffic conditions in any particular block, the track relay for that block will be energized so as to complete the circuit including the coils 7 of the inductor at the entrance end of such block, while under danger conditions this circuit will be opened at the contact finger 9 and front contact of the controlling track relay. While the control of the inductors has been shown only for clear and danger, it is obvious that the inductor circuit could be controlled so as to be made under clear conditions, and broken under both caution and danger conditions, in any usual or desired manner, such for instances, as shown in the patent to W. K. Howe No. 1,604,098 of October 19, 1926, which employs a line relay controlled by the second block in advance of any particular inductor, to cause opening of the inductor circuit under caution conditions.

Carried on the car which is represented diagrammatically by axles and wheels 10, is a receiver including a rectangular, annular, core 11, carrying primary coils P^1 and P^2 and secondary coils S^1 and S^2 . The core 11, as well as the inductor bars 6, is preferably made of laminated material, in order to cut down alternating current losses.

The primary coils P^1 and P^2 are connected in series with each other, and with a tuning condenser 12, and a source of alternating current 13, preferably of a frequency, higher than the usual commercial frequencies, such as 360 cycles per second, for example.

The secondary coils S^1 and S^2 are likewise connected in series with each other, with a tuning condenser 14, and a main control relay MR. The primary and secondary circuits just described are thus tuned for the frequency of the alternating current supplied by 13.

The system includes an electro-magnetic device, or its equivalent, EPV, which is nor-

mainly energized through a circuit including a source of energy 15 shown as a battery and a contact finger 16 and front contact of relay MR, and is arranged to either operate the usual car air brakes, upon de-energization, or to impose any other desired train movement restriction.

As described above, the primary circuit including the primary coils P^1 and P^2 is continuously supplied with alternating current, which results in magnetic flux being produced in the core 11 which travels through two separate paths, as indicated by the dash line arrows in Fig. 1, thus inducing voltages in the secondary coils S^1 and S^2 which are additive to cause sufficient current to flow through the secondary circuit including main relay MR to normally energize such relay and maintain the brake device EPV in energized condition.

The trackway inductors are positioned to be passed over by the car carried receiver and to inductively co-act therewith through an air gap, whereby to exert influences on the receiver in accordance with traffic conditions ahead. In the case where an inductor is open circuited, a secondary magnetic path is furnished for the primary flux in the receiver core 11, whereby, when the receiver is directly over the inductor, part of the flux from primary coils P^1 and P^2 tends to flow through the entire length of the front and rear sides, respectively, of the core 11, then pass downwardly to the end of the adjacent bar 6, through such bar, and up from the other end of such bar back to the receiver core 11, thus tending to cause flux to flow through the secondary coils S^1 and S^2 in the direction opposite to the original direction of flow. The paths followed by flux, in the receiver, when unaffected by an inductor, are shown in Figs. 1 and 2, by dash line arrows, while the added paths for flow of flux, when over an active (open circuited) inductor, are shown by dotted line arrows in Fig. 2. Thus in the case of each secondary coil, flux tends to pass therethrough in opposite directions, through separate paths, and the reluctances of these separate paths are so adjusted by proportioning the inductor and receiver and the space therebetween, as to make them approximately equal. In these circumstances, the flux passing through the secondary coils S^1 and S^2 is reduced to zero, or substantially zero, thereby to de-energize relay MR and cause an automatic brake application due to de-energization of the brake device EPV.

In the case of the train entering a clear block, the coils 7 of the inductor at the entrance to such block, are included in a closed circuit, and these coils 7 exert so great a choking action against flux passing through the bars 6, that they offer practically no better pathway for flux than if the resultant in-

ductor were entirely absent. Under such conditions, the receiver passes over the inductor without having any material change made in the flux distribution therein, and accordingly, the relay MR is not affected. Thus, on entering a clear block, no brake application is incurred, but on entering a danger block, (or a caution block if such control be provided, as referred to above) on passing the signals at the entrances to such block, a brake application is incurred.

The form of invention shown in Fig. 2, is different from that just described only with respect to the trackway inductor. This inductor 17 comprises a single bar, rather than spaced parallel bars, and is positioned to be symmetrically arranged below, and parallel with, the receiver, when a car passes thereby, in the position shown in Fig. 2. The control of the inductor 17, through its coil 17¹, by traffic conditions, is identical with that of the first case, and its effect on the receiver with regard to the flux distribution in the receiver core, is substantially the same as above described. As shown in Fig. 2, the receiver is directly over the inductor 17, in its active, or open circuited, condition, with the resulting change in flux flow tendency as indicated by the dotted and dashed arrows in such circumstances, relay MR is de-energized, as is also the brake device EPV and thus a brake application is incurred.

From a consideration of the above described interaction between the receiver and an inductor in active condition, it will be seen that by properly proportioning and adjusting the different elements, the reluctances of the alternative paths for the flow of magnetic flux produced by the primary coils P^1 and P^2 can be made substantially equal, to thus reduce the resultant induced secondary current substantially to zero. If these reluctances be unequal depending upon which path has the greater reluctance, a small current, but insufficient to energize relay MR, will flow in the secondary circuit including this relay.

Instead of having the described inductors and receiver control brake control means which are absolute in their action, the system could include any usual acknowledging and reset devices, such, for instance, as shown in the Howe Patent 1,604,098, referred to above, whereby an acknowledging act would permit the train to pass a signal at stop or caution, without incurring a brake application and the reset device would be employed to restore the parts to normal after the incurrence of an automatic brake application due to failure to properly acknowledge on passing an active inductor.

The above rather specific description of one form of the invention, is shown solely by way of example, and is not intended, in any manner whatsoever, in a limiting sense. Ob- 100

viously, the invention can assume many different physical forms, and is susceptible of numerous modifications, and it is intended to include, in this application, all such forms and modifications as come within the appended claims.

Having described my invention, I now claim:—

1. In a train control system, a car-carried receiver including a closed loop core, two primary coils on the core, positioned on opposite sides of the core and in staggered relation to each other, two secondary coils on the core, placed on opposite sides of the core and in staggered relation to each other, means for energizing the primary coils, and means controlled by the secondary coils for controlling train movement.

2. In a train control system, a car-carried receiver including a closed loop core, primary coils on the core, secondary coils on the core, means for energizing the primary coils with alternating current, means controlled by the secondary coils for controlling train movement, and an inductor, positioned in the track-way in inductive relation to said receiver core and coils and controlled in accordance with traffic conditions ahead.

3. In a train control system a car-carried receiver including a closed loop core, two primary coils on the core, positioned on opposite sides of the core and in staggered relation to each other, secondary coils on the core, placed on opposite sides of the core and in staggered relation to each other, means for energizing the primary coils, means controlled by the secondary coils for controlling train movement, and an inductor, controlled in accordance with traffic conditions ahead, arranged to inductively affect the receiver.

4. In a train control system, a car-carried receiver including a closed loop core, two primary coils on the core, placed on opposite sides of the core and in staggered relation to each other, two secondary coils on the core, placed on opposite sides of the core and in staggered relation to each other, means for energizing the primary coils, means controlled by the secondary coils for controlling train movement, and a single bar inductor, controlled in accordance with traffic conditions ahead, arranged to inductively affect the receiver.

5. In a train control system, a car-carried

receiver including a closed loop core positioned in inductive relation to the road bed, primary coils on the core, secondary coils on the core, means for energizing the primary coils with alternating current, means controlled by the secondary coils for controlling train movement and a single bar inductor positioned in the road bed, controlled in accordance with traffic conditions ahead, and arranged to directly inductively affect the receiver.

6. In a train control system, a wayside inductor, controlled in accordance with traffic conditions ahead, a car-carried receiver including an annular, substantially rectangular, core, primary coils on opposite sides of the core and in staggered relation to each other, means to energize the primary coils, with alternating current, secondary coils on the core arranged symmetrically with respect to the primary coils, and train movement restricting means controlled by the secondary coils.

7. In a train control system, a wayside inductor, in the form of a single bar of magnetic material, controlled in accordance with traffic conditions ahead, a car-carried receiver including an annular, substantially rectangular, core, positioned parallel with, and symmetrically to, the inductor, primary coils on opposite sides of the core and in staggered relation to each other, means to energize the primary coils, in series, with alternating current, secondary coils on the core arranged symmetrically with respect to the primary coils, and train movement restricting means controlled by the secondary coils.

8. In a train control system, a car-carried receiver including an annular, substantially rectangular, core, primary coils on opposite sides of the core and in staggered relation to each other, means to energize the primary coils, in series, with alternating current to cause flow of flux through the core, secondary coils on the core arranged symmetrically with respect to the primary coils, train movement restricting means controlled by the secondary coils, and traffic controlled means tending to at times cause a reversal in the direction of the flow of flux through the secondary coils.

In testimony whereof I affix my signature.

RICHARD C. LEAKE.
